BUFFING FIXTURE FOR DRY SHAVER
CUTTERHEADS

Thomas J. Murphy, Stamford, Conn.

Application May 8, 1946, Serial No. 668,164

7 Claims. (Cl. 51—217)

1

This invention relates to a buffing fixture for the cutter head of dry shavers, more particularly to a holder for holding the outer cutters of a dry shaver cutter head during the buffing operation in finishing these cutters, and has for an object to provide a simple and effective holder for holding the cutter elements in proper relation to each other and also to support the cutting teeth during the buffing operation so as to secure uniform and accurate buffing of all of the teeth of the cutter, and prevent buffing off too much of the tips of the teeth, so they will not be made too sharp with the liability of causing irritation when shaving.

Another object is to reduce to a minimum variations in buffing due to variations in pressure of the article against the buffing wheel.

A further object is to increase control of the operator over the buffing operation.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a side elevation of one form of my improved fixture with a plate of the cutter head clamped in position for buffing;

Fig. 2 is an end view thereof;

Fig. 3 is a top plan view of one end portion thereof;

Fig. 4 is an end view showing a slight modification;

Fig. 5 is a transverse section of one form of cutter head;

Fig. 6 is a top plan view of a portion thereof;

Fig. 7 is a vertical section of one of the cutter plates removed;

Fig. 8 is a top plan view thereof;

Fig. 9 is an elevation looking from the right of Fig. 7;

Fig. 10 is an end view of the upper portion of the fixture with cutter plates clamped thereon showing how the device may be modified for different cutters; and

Figs. 11 and 12 are similar views showing other ways the holder may be modified for different buffing effects.

This device is designed primarily for use in buffing cutter heads of the type comprising separate side plates each carrying a row of the outer cutter teeth of the cutter head of an electric dry shaver of the type disclosed in my Patents No. 2,264,398, December 2, 1941, and No. 2,395,495, February 26, 1946. Such a cutter head is illustrated somewhat diagrammatically in Figs. 5 and 6, the individual plate of the outer cutter being shown separated from it in Figs. 7, 8 and 9.

It is to be understood that in all views of the drawing the scale is greatly enlarged and features are also exaggerated, because the actual cutter heads themselves are quite small and dimensions are figured in thousandths of an inch.

The type of cutter head shown in Figs. 5 and 6 comprises a central block 10 on the opposite sides of which are secured plates 11 by any suitable means, as by clamping means or soldering, which plates are wider than the block so as to extend a suitable distance above it, and each at its separate edge terminates in an inturned flange 12 provided on its free edge with a series of cutter teeth 13. The flange and the teeth are at an angle of about 100 degrees with the plate 11 so that they incline upwardly toward the center, as shown in Fig. 5, so that they are adapted for a certain amount of lateral rocking back and forth when pressed against the surface of the skin in the shaving operation to maintain them in proper contact with the skin, and also to facilitate movement over the surface of the skin, all as clearly disclosed in the above noted patents. The block 10 is of such a width in relation to the width of the flanges 12 that when the plates are mounted on the block the free ends of the teeth 13 of the outer cutter are spaced laterally to form a longitudinal slot 14. In the space between these plates, their flanges and the top of the block 10 is the reciprocating cutter 15 which is substantially rectangular in cross section and hollow and is guided for reciprocating movement on the block 10 and between the side plates 11. On its top it is provided with two sets of cutter teeth 16, running on the inner side of the outer teeth 13 and cooperating therewith to cut the hairs during the shaving operation with a shearing action in the well known manner. The movable cutter 15 is operated by any suitable motor (not shown) through any suitable driving connection, indicated as an operating rod 17. It will be understood this head is mounted in one end of the casing enclosing the motor and which forms a handle for pressing the cutter head against the surface of the skin and moving it thereover during the shaving operation; but these elements are not shown as they form no part of this invention.

In making the device the plates 11 forming the outer cutter of the head are made and finished separately and then assembled. The final opera-

tion in finishing the cutter teeth 13 is the buffing operation, and in buffing such single elements the operator is liable to remove too much metal from the tips of the teeth, it being understood that the teeth are very small and thin in order to bring the cutting or shearing plane as close as possible to the surface of the skin to secure a close shave. Removing too much metal from the tips of the teeth is liable to make them too sharp, with the result that they cause irritation while shaving. Also, the buffing may substantially shorten the teeth, which would be serious in some types of cutters, especially the types of cutters using very short teeth. Also when buffed unsupported, as the outer surfaces of the teeth are pressed against the buffing wheel they will yield so that the operator does not have good control and the pressure may vary from one plate to another, thus not giving uniform buffing for different plates.

I have found that if the plates of the cutters are clamped on the fixture and opposed to one another so that the teeth on the two elements register, and the teeth are backed up or supported on the opposite side from the surface held against the buffing wheel, there is no danger of removing too much metal from the tips of the teeth, and the buffing can be continued longer with a coarser abrasive so that the upper surrounding edges of the teeth will be rounded off, and when assembled in the head will bring the inner movable cutter closer to the surface of the skin and will therefore produce a closer and smoother shave with less irritation to the skin. Such a device for holding the cutter plates is shown in Figs. 1 to 4 and 10 to 12, and while there are many other ways of clamping and holding the plates on the fixture, that shown is very simple and effective and may be quickly operated to secure and release the plates.

This fixture comprises a body or block 18 preferably of metal inclined in its upper portion on its opposite sides 19 to which the plates 11 of the cutter head are clamped, corresponding to the angle between the body of the plate and its flange 12 on which the cutting teeth are formed, so that the teeth will rest against the upper edge 20. As indicated above, this angle is preferably about 100 degrees and is indicated at 21 on the drawing, but it is to be understood that neither the block nor the cutter head plates are limited to this specific angle, as it may be found desirable under different conditions to vary it somewhat either way. As indicated, the cutter head plates 11 are clamped on the opposite side walls 19 of this block with the teeth 13 resting against the top edge of the block, as shown in Fig. 2. Any suitable means may be used for clamping these plates, but that shown comprises the knurled nuts 22 each threaded on a screw 22a secured in the block. One way is by threading into a tapped opening in the block. The screw passes through a clamping plate 35 on each side provided with a flange 36 on its lower edge seated in a groove 37 in the side of the block and a flange 38 at its upper edge clamped against the plate 11 by the clamping nut 22. This securing or clamping means has proved very satisfactory and may be easily and quickly manipulated. As suggested, the teeth 13 of the two plates for best results should be in alignment when assembled on the block, as shown in Fig. 3, and to assure proper alignment of the teeth one or more slots 23 can be punched and ground to accurate width to engage over one or more locating pins 24 mounted in the block. The block may be of such a width

that the tips of the opposed teeth touch each other, or they could be somewhat spaced, as is found desirable. It may in some cases be best that a small space be left between them, so that the buffing wheel may enter for the buffing operation.

It will be understood that as the outer surfaces of these teeth are held against the buffing wheel, a portion of which is indicated in dotted lines at 25, Fig. 2, the teeth are supported by the block 18, so that they do not yield and the pressure can be more accurately controlled and a much better and more uniform job can be done. Besides, two plates can be buffed at the same time, thus increasing production as well as producing a better cutter. Each plate automatically protects the other so that the teeth are protected and there is not too much of their tips buffed off to make them too sharp with the liability of causing irritation in shaving. If desired, hand grips 26 may be provided on opposite ends of the block 18. It is preferred that the length of the upper portion of the block 18 be made less than that of the cutter plates 11, so that they will overhang somewhat as shown at 9 in Figs. 1 and 3 to protect the fixture from the buffing compound.

In the modified arrangement of Fig. 4, the block 27 corresponding to the block 18 is relieved or provided with a longitudinal central channel 28 in its upper edge and the cutter plates 11 are mounted the same as in Figs. 1 to 3, but the teeth 13 may be spaced a short distance because of this channel, but should practically contact each other. They will be supported on the end portion 29 of the block, the same as in the first arrangement. The channel 28 is to collect buffing material, or, that is, to prevent caking of grinding compound between the teeth in the buffing operation.

If wider slots are used between narrower teeth, the buffing is more effective in rounding off upper edges of the teeth in the outer shaving member. While the teeth in Figs. 2 and 4 are shown in substantially the same plane, they may be slightly depressed in the center, as shown at 30 in Fig. 11, or they can be slightly raised as shown at 31 in Fig. 12, these arrangements being exaggerated in the drawing. Also the clamping plates 35 are omitted in these figures, but it is to be understood such clamping plates are used to hold the cutter plates 11 the same as shown in Figs. 1 and 2. Whether they are in the same plane, depressed in the center or slightly raised, may be controlled by the angle of inclination of the side walls of the block. Thus, in Fig. 2 the end wall 20 is made substantially horizontal and the clamping side walls 19 are at an angle substantially equal to the angle between the body of the plate 11 and the flange 12. In the arrangement of Fig. 11 the end wall may be left horizontal or slightly depressed in the center, and the side walls, indicated at 19a, of the block 18a, inclined at a greater angle, the angle corresponding to the angle 21 being shown in dotted lines 32. In Fig. 12, the sides 19b of the block 18b are inclined at a less angle, the old angle being shown by the dotted lines 33. Then when the plates 11 are clamped to these walls, the teeth will be raised slightly in the center, as indicated at 31, and therefore the end walls 34 may be similarly inclined or raised somewhat at the center so as to provide support for the teeth 13 during the buffing operation. In the use of very short teeth, the side walls corresponding to the walls 19 may be made straight or parallel, as indicated at 19c in Fig. 10. In this case the angle between the body of the

plate 11a and the flange 12a is substantially a right angle, the upper portion of the block being shown at 18c.

These figures show how the block may be varied to accommodate different cutter plates and also for different types of buffing operations, and still have the teeth supported by the block during buffing.

In production, the teeth on the plate can be punched and consequently the tips and base slots between the teeth can be rounded or any approximation thereof for best results. All burs left by the punch on the inner or under sides of the teeth are removed by grinding and lapping.

Having thus set forth the nature of my invention, I claim:

1. A buffing fixture for cutter head plates which plates each include a body and a flange at one edge extending laterally to the body and provided with a series of teeth on its free edge, said fixture comprising a block provided with opposite side walls and an intermediate wall arranged with the side walls each at an angle to the intermediate wall equal to substantially the angle between the body and flange of the plates, and means for clamping the bodies of a pair of said plates against the opposite side walls of the block with the teeth of each plate resting against the intermediate wall and supported thereby.

2. A buffing fixture for cutter head plates which plates comprise a body plate portion and a lateral flange at one edge terminating in a row of cutter teeth, said fixture comprising a block provided with opposite side walls and an intermediate wall connecting them, and means for clamping a pair of said cutter head plates against the opposite side walls of the block, said clamping means being arranged to clamp the body plate portions against the side walls of the block with the teeth of said plates resting on and supported by the connecting intermediate wall.

3. A buffing fixture for cutter head plates which plates comprise a body plate portion and a lateral flange at one edge terminating in a row of cutter teeth, said fixture comprising a block provided with opposite side walls and an intermediate wall connecting them, the side walls being inclined toward each other outwardly toward said intermediate wall, and means for clamping said cutter head plates to the block with their body plate portions against the side walls of the block and the teeth resting on the intermediate wall.

4. A buffing fixture for holding cutter head plates which head plates comprise a plate like body portion and a lateral flange along one edge terminating in a row of cutter teeth, said fixture comprising a block including opposite side walls and an intermediate wall between them arranged at an angle to each side wall substantially the same as the angle between the body and the flange of said head plate, and means for clamping the plates on the block with their body portion against said side walls of the block and with their teeth on the intermediate wall and supported thereby.

5. A buffing fixture for holding cutter head plates which head plates comprise a plate like body portion and a lateral flange extending at an angle to the plate like portion along one edge

terminating in a row of cutter teeth, said fixture comprising a block including spaced side walls and an intermediate wall connecting the side walls, each said side and intermediate walls being at an angle to each other substantially the same as the angle between the body and flange of the head plates, means for clamping a pair of said plates on the opposite sides of the block arranged with one body portion on each side wall of the block and with its teeth on the intermediate wall and with the tips of the two rows of teeth adjacent, and locating means on the block arranged to cooperate with means on the plate to locate the teeth of the two plates in alignment.

10 6. A buffing fixture for holding cutter head plates which head plates comprise a plate like body portion and a lateral flange along one edge terminating in a row of cutter teeth, said fixture comprising a block including opposite side walls and an intermediate wall between them arranged at an angle to each side wall substantially the same as the angle between the body and the flange of said head plate, hand grips extending outwardly from the opposite ends of the block, 20 and means for clamping the plates against the opposite sides of the block with their body portions against said side walls of the block and with their teeth on the intermediate wall and supported thereby.

25 7. A buffing fixture for holding cutter head plates which head plates comprise a plate like body portion and a lateral flange along one edge terminating in a row of cutter teeth, said fixture comprising a block including spaced side walls and an intermediate wall located between the side walls, each said side and intermediate walls being at an angle to each other substantially the same as the angle between the body and flange of the head plates, means for clamping a pair of 30 said plates on opposite sides of the block arranged with one body portion on each side wall of the block with teeth of the plates on the intermediate wall and supported thereby, said intermediate wall being of a width so that the tips of the teeth of the two plates practically contact, and said block being provided with a longitudinal groove in said intermediate wall under the tips of the teeth of the two plates.
